UNITED STATES PATENT OFFICE.

JOHN A. RULE, OF CINCINNATI, OHIO.

COIN-OPERATED VENDING-MACHINE.

No. 822,869.

Specification of Letters Patent.

Patented June 5, 1906.

Application filed December 31 1904. Serial No. 239,087.

To all whom it may concern:

Be it known that I, JOHN A. RULE, a citizen of the United States of America, and a resident of Cincinnati, county of Hamilton, 5 State of Ohio, have invented certain new and useful Improvements in Coin-Operated Vending-Machines, of which the following is a specification.

The object of my invention is a vending- 10 machine in which a coin of larger denomination actuates both the delivery mechanism and the change-receptacle and a small coin actuates only the delivery mechanism.

In the accompanying drawings I have illustrated 15 the coin-actuated part of a vending-machine.

Figure 1 is a side elevation of the same. Fig. 2 is a front elevation of the same, the coin-receptacle being shown in section. Fig. 20 3 is a detail rear elevation of the ends of the coin and the change chutes. Figs. 4 and 5 are detail perspective views of the levers which regulate the delivery mechanism and the change-receptacle.

25 Referring to the parts, the delivery mechanism is represented only to such an extent as is necessary to understand my invention. The delivery mechanism as here illustrated consists of a shaft A, which carries a coiled 30 spring a and a ratchet-wheel a' and a swinging arm a², which is adapted to open the doors of a paper-receptacle when it is rotated as described in my application which was filed on August 14, 1903, Serial No. 169,440, for a 35 coin-operated vending-machine.

In the present construction coin-chute B is divided by a partition b into passages b' b². The passage b' at the upper end of the chute is extended into a coin-slot b³, the partition b 40 being cut away adjacent to the opening b', leaving ledges b⁴ at a distance apart such as to support a coin of a larger diameter, such as a nickel, and to allow a smaller coin, such as a cent, to pass between the ledges. 45 Pivoted below the ledges b⁴ is a leaf b⁵, whose lower end stands normally adjacent to a flange b⁶. The leaf b⁵ at its loose end rests upon the end of a lever b⁷, which may be regulated by an arm b⁸ so that the weight b⁹ upon 50 the end of the lever will be overbalanced by the weight of the number of small coins desired when resting on the leaf b⁵, so as to carry it below the flange b⁶ and direct the small coin into the chute b².

55 At its lower end the passage b² is intercepted by a block c upon an arm C of a bell-crank

lever which is fulcrumed at c' and carries upon its other arm c² a pawl c³, the pawl being held normally in contact with the teeth of the ratchet a' by a spring c⁴. When a coin or 60 coins in falling through passage b² strikes the block c, they carry the pawl c³ out of contact with the tooth of the ratchet a' and allow the ratchet-wheel a' to move through one step, thereby moving arm a² through one step, 65 which releases the article to be vended.

The passage b' is intercepted at its lower end by a block d upon the end of an arm D of a second bell-crank lever which is fulcrumed at d' and has its other arm d² brought in contact with lever E, which is fulcrumed at e and has at its upper end a hook e' for engaging the successive lugs f of a sliding change-receptacle F. The arm D is bent at d³, passes upon the outside of the passage b², and enters passage b' from the side and is guided by a bracket b¹⁰, secured upon the outside of the coin-chute. The block d stands above the end of the block c', so as to contact the same when it is carried downward.

70 The change-receptacle consists of vertical sides f', joined by inclined partitions f², forming compartments for the reception of change, the compartments being brought successively to register with the slot g, leading into the change-chute G, when the operation of the lever E permits the tooth e' to be carried from one of the teeth f to the next tooth upon the change-receptacle.

75 The operation of the device is as follows: 90 If a two-cent paper is to be vended, the compartments f' each receive three cents and the change-receptacle is set in its uppermost position with the lowermost of the compartments f' standing just one step above the slot g. The lever b⁷ is regulated by means of the arm b⁸, so that the leaf b⁵ will be carried below the partition b⁶ by the weight of two cents. If two cents be placed in the slot b³, they will then be carried into the passage b², 100 will strike the block c without affecting the arm D, causing it to stand upon the outside of the passage b², and will release the pawl c³ from the ratchet, thereby turning the delivery mechanism through one step. If a nickel be placed in the slot b³, it is carried by ledges b⁴ into the passage b'. It strikes the block d', lowers both the arm D and the arm C, which carries the pawl c³ out of contact with the ratchet a', allowing it to move through one 105 step, and causes the arm d² to throw the lever E and carry the tooth e' out of contact with 110

the tooth f it has been engaging and allows the change-receptacle to drop down one step, causing the compartment f' to register with the slot g^3 , through which the pennies in the compartment pass into the change-chute G because of the inclined bottom of the compartments.

What I claim is—

- 5 1. In a coin-operated vending-machine the combination of a delivery mechanism, a locking mechanism for the delivery mechanism, a movable change-receptacle, means for locking the change-receptacle, a passage for large coins, a second passage for small coins, a releasing mechanism for the delivery mechanism adapted to be actuated by a coin in either passage and a releasing mechanism for the change-receptacle to be actuated by a coin in the first passage.
- 10 2. In a coin-operated vending-machine the combination of a coin-chute having a passage for large and a passage for small coins, means of directing large coins into the first passage and small coins into the second passage, a delivery mechanism, a lever for locking said mechanism one of whose ends extends into

- 20
- 25

the second passage, a movable change-receptacle, and a second lever for actuating the change-receptacle and the first lever and whose end extends into the first passage.

3. In a coin-operated vending-machine the combination of a main shaft, a means of exerting a rotating pressure upon the shaft, a ratchet-wheel upon the shaft, a sliding change-receptacle, a lever for engaging the change-receptacle, a coin-chute having a passage for large and a second passage for small coins, a bell-crank lever one of whose arms engages the ratchet-wheel and the other arm of which extends into the second passage, a second lever one end of which engages the lever which holds the change-receptacle and the other arm of which extends around the second passage and into the first passage above the bell-crank lever so that a small coin actuates the delivery mechanism and a large coin actuates both the delivery mechanism and the change-receptacle.
